HOOD ORNAMENT FOR AN AUTOMOBILE

John E. Schwarz, Oak Park, Mich., assignor to Chrysler Corporation, Highland Park, Mich., a corporation of Delaware

Application January 26, 1955, Serial No. 34,233

Term of patent 14 years

(Cl. D14—18)

Fig. 1 is a plan view of a hood ornament for an automobile showing my novel design;

Fig. 2 is a side elevational view thereof;

Fig. 3 is a sectional view taken on the line 3—3 of Fig. 1; and

Figs. 4, 5, 6 and 7 are sectional views taken on the lines 4—4, 5—5, 6—6 and 7—7 of Fig. 2.

I claim:

The ornamental design for a hood ornament for an automobile, substantially as shown.
